EXPLOSION ENGINE

Carlos Ballester Molina, Buenos Aires, Argentina

Application January 26, 1940, Serial No. 315,848

5 Claims. (Cl. 123—122)

This invention relates to improvements in explosion engines, and particularly to the cooling of the cylinders.

While it is true that important improvements have been developed lately in explosion engines, no great progress has been made in the cooling of cylinders, which is still obtained through circulation of water or air.

The improvements subject of the present invention are applicable to any type of explosion engine, and are based on a physical principle so combined that a real self-refrigeration is obtained without any additional consumption of power and in the most simple manner.

The present invention uses the heat of the cylinders in operation to produce a physical reaction in the gas coming from the carburetor, which will result in the necessary cooling to absorb a large amount of the heat caused by the explosions, with the additional advantage of providing a recarburation of the fuel that will render the effect more effective when burning in the cylinder chamber.

For this purpose, the admission pipe from the carburetor to the inlet of the cylinder passes through a conduit adjacent to said cylinder, so as to receive sufficient heat to vaporize the mixture before entering the chamber, and as during this transformation of the fuel a cooling is produced which absorbs the surrounding heat, the suctioned fluid acts as a sufficient refrigerant to avoid overheating of the cylinder. This may be aided, if desired, by other cooling means cooperating with this automatic cooling.

In order that the invention may be more clearly understood and readily carried into practice, same has been illustrated by way of example and in a preferred embodiment in the accompanying drawing, wherein the single figure is a view of an engine provided with the means for obtaining self-cooling, showing the manner in which vaporization is caused by the heat received from the cylinder itself.

With reference to the drawing, *a* indicates the body of the engine which usually comprises two or more cylinders *1* with respective pistons *2* having connecting rods *3* connected to the pins of crank *4*.

The explosion engine has the corresponding carburetor *b*, the outlet of which is coupled to the admission pipe *c*, in the present instance branched so as to lead to the inlets *5* of the cylinders *1*.

The inlets *5* are closed by valves *6* through the pressure of a spring *7* centered on stem *6'*. Each

5 stem *6'* is connected to a lever *8* fulcrumed on a bridge *9*, the opposite end of said lever being joined to a rod *10* which by means of a slide *11* is connected to the eccentrics of the cam shaft *12*.

As is customary in engines of this type, each cylinder *1* has an exhaust pipe for the exhaust of burned gases, and the engine also comprises a corresponding electric ignition system with a spark plug in the chamber of each cylinder.

10 The present invention takes advantage of the working heat of the pistons *2* in order to obtain a self-refrigeration, and for this purpose the admission pipe, in leading to the inlet *5* of each cylinder *1*, passes through a length of conduit *13* arranged adjacent to the cylinder to be fed.

15 Due to the fact that the conduit *13* has a common wall with the cylinder, the heat generated by the explosions is irradiated directly towards the interior of said length of conduit *13*.

Upon effecting the suction by the stroke of the piston *2*, valve *6* opens due to the control of cam shaft *12* which displaces the slide *11* of rod *10*.

20 With such suctioning effect, the gasoline or gasoline gas mixed with air in the carburetor passes through the admission pipe *c* and on reaching the conduit length *13*, is vaporized due to the heat irradiated from cylinder *1*. This means that the fuel suffers a transformation or 25 change resulting in the consequent cooling, and logically will absorb the surrounding heat, thereby cooling the adjacent cylinder *1*.

For this irradiation effect, the walls separating the cylinder and the conduit *13* are made of 30 good heat conducting metal.

Apart from acting as a refrigerant, the fuel on 35 vaporizing and absorbing the surrounding heat, acquires a condition which favors combustion, and due to the fact that it has been transformed 40 into vapor, it is more highly carburating, as if it had been subject to recarburation. Therefore, on entering the chamber of cylinder *1*, it will produce a more effective action with the consequent 45 increase in efficiency.

Therefore, the suction of the mixture of fuel and air derived from the carburetor *b*, upon passing through the conduit *13*, will produce the cooling of the same cylinder and at the same time cause a recarburation or preparation of the 50 fuel in highly carburating conditions.

If desired, apart from the length of the admission pipe arranged adjacent to the cylinder *1*, other water or air cooling means may be combined to cooperate therewith.

The length *13* is parallel to cylinder *1*, but it

may also be located diagonally thereto or helically, if preferred.

It is evident that the invention as described above is capable of several modifications in construction and detail, provided they fall within the scope of the invention as clearly set forth in the appended claims.

What I claim is:

1. An improvement in internal combustion engines comprising cylinders, pistons reciprocating in said cylinders, a main conduit for providing carbureted air to said cylinders having a point of bifurcation therein, a pair of admission conduits leading to said cylinders from said point of bifurcation, said admission conduits having a portion of their length located adjacent to each cylinder, said admission conduits also having a constant cross-section from said point of bifurcation to the inlet of each cylinder so that said portion of the admission conduits located adjacent to each cylinder is not deformed and follows a straight line substantially parallel to the longitudinal axis of each cylinder.

2. An improvement in internal combustion engines as set forth in claim 1 wherein the admission conduit has a constant cross-section from the point of bifurcation from the main conduit to the point where it enters the cylinder, whereby in maintaining its cross-section, said conduit

has contact by means of a simple length or linear portion of the cylinder walls.

3. An improvement in internal combustion engines as set forth in claim 1 wherein the portion of the admission conduit located adjacent the cylinder is longitudinal thereto, and wherein said conduit, without surrounding the cylinder, only contacts the wall of said cylinder in a linear portion thereof.

4. An improvement in internal combustion engines comprising cylinders, pistons reciprocating in said cylinders, a carburetor, a main conduit leading from said carburetor to the inlets in said cylinders, said main conduit being divided into two branches and said branches from the dividing point to the respective inlets having a constant cross-section, each branch of said main conduit having a linear portion in contact with the walls of a cylinder in such a way that said portion of the branch follows a straight line parallel to the virtual axis of the cylinder.

5. An improvement in internal combustion engines as set forth in claim 4 in which said two branches extend longitudinal to the cylinder at the portion thereof adjacent each cylinder and each branch has contact with only one linear length of the wall of the cylinder.

CARLOS BALLESTER MOLINA.
